UNITED STATES PATENT OFFICE

HENRY J. STUART, OF NEW HAVEN, CONNECTICUT, ASSIGNOR TO THE BASSETT METAL GOODS COMPANY, INC., OF DERBY, CONNECTICUT, A CORPORATION OF CONNECTICUT

HOSE SUPPORTER

Application filed November 5, 1929. Serial No. 404,894.

This invention relates, generally, to improvements in hose supporters or garters; and the invention has for its principal object to provide an improved stocking or hose gripping structure adapted to furnish an exceedingly efficient hold upon the stocking or hose body, but in such manner as to avoid risk of injury to even the most delicate and sheer fabrics of which the stocking or hose may be made.

With the general object above mentioned in view, this invention provides a novel construction of resilient collet or button to cooperate with the gripping loop of the garter clasp, together with a mounting for said collet or button, whereby a flat or smooth bottomed support for the latter is furnished, to the end that substantially no irritation to the leg of the wearer arises, and a comfortable stocking gripping means of minimum bulk is provided.

Furthermore, the invention has for an additional object to provide a novel construction of collet or button for garter clasps, which is reenforced with respect to the body thereof per se, both for the purpose of increasing its durability and preventing chipping, breaking or other deformations thereof, as well as for the purpose of increasing the inherent resiliency thereof.

Other objects of this invention, not at this time more particularly enumerated, will be clearly understood from the following detailed description of the same.

An illustrative embodiment of the novel garter clasp made according to and embodying the principles of this invention is shown by the accompanying drawings, in which:

Fig. 1 is a face view (in part) of a stocking supporter equipped with the novel clasp structure made according to and embodying the principles of this invention, the latter being shown in operative gripping or holding relation to a stocking body; Fig. 2 is a transverse vertical section, taken on line 2—2

in Fig. 1, but drawn on an enlarged scale;

Fig. 3 is a plan view of the novel collet or button and its mounting or base plate, with the gripping loop removed; Fig. 4 is a side elevation of the parts shown in Fig. 3; and

Fig. 5 is a transverse vertical section, taken on line 5—5 in Fig. 3.

Similar characters of reference are employed in all of the hereinabove described views, to indicate corresponding parts.

Referring now to said drawings, the reference character 6 indicates the suspension strap of a garter, which may be of any well known type or construction, and which carries at its lower extremity the coupling loop or member 7 (usually made of metallic wire or as a metal stamping), and which provides a connecting support for the button strap 8 of the garter clasp per se, and through the pivoting link 9, also mounted thereon, a pivotal connection or hinge for a gripping loop 10.

Mounted on the button strap 8 is a carrier or base-plate 11 for supporting the collet or button of the garter clasp. Said carrier or base-plate 11 is provided, adjacent to its upper and lower ends respectively, with transverse slots 12 and 13, through which the body of the button strap 8 is threaded to engage and hold said carrier or base in desired fixed position thereon.

The novel collet or button carried by the carrier or base-plate 11 comprises a resilient body or element of peculiar construction and shape, which is made of molded rubber stock. This body or element consists in a unitary structure including a head or top-portion 14, the upper surface of which is preferably rounded to provide a convex contour. The periphery of said head or top-portion 14 is undercut to provide an inwardly and downwardly inclined peripheral shoulder 15. Extending downwardly from said shoulder 15 is a shank 16 which is preferably slightly tapering, from the point of juncture with said peripheral shoulder 15 of the head or top-portion, downwardly and inwardly toward its bottom end. The bottom of said shank 16 is formed to provide an upwardly depressed concavely hollowed portion 17 whereby the mass of the shank or base portion is reduced, to thereby render the external parts of the shank more springy or resilient, as well as to provide space for disposing the anchoring structure of the collet or button above the bot-

tom plane of the carrier or base plate 11, so that the bottom surface of the latter element may possess a smooth flat surface free from projections, and consequently adapted to 5 avoid irritation to the leg of the wearer, and thus insure greater ease and comfort to said wearer; in the addition to these advantages, the construction described permits of the use of a collet or button having a minimum 10 height, and consequently one less likely to produce bulges which are apparent in and through thin dresses or gowns when the garter structure is worn by women. The collet or button, having the general external contour or shape above described, is provided 15 with a central or axial bore 18, terminating at its upper end in a counter-sunk seat 19 of enlarged diameter.

To mount the collet or button in assembled 20 and secured relation to the carrier or base-plate 11, the latter is provided with an upwardly pressed perforate portion to form a substantially conical shoulder 20, which rises above the plane of said carrier or base-plate 25 so as to extend into the hollowed portion 17 of the collet or button to be mounted thereon. The reference character 21 indicates a fastening rivet or post, substantially corresponding 30 in diameter to that of the bore 18 of the collet or button, and having at its upper end an annular enlargement or head 22 adapted to seat itself in the counter-sunk seat 19 of said collet or button. The lower end of said rivet or post 21 is of reduced diameter to provide a 35 riveting lug 23 whereby a shoulder is formed to engage upon the conical shoulder 20 of the carrier or base-plate 11, while the riveting lug 23 extends through the perforation defined by said conical shoulder 20, to be headed or crushed over the underside of the marginal portions of the latter, thereby securing said rivet or post to said carrier or base-plate 40 11. With headed over or riveted lug 23 contained within the limits of the space beneath the conical shoulder 20 and above the bottom plane of said carrier or base plate 11, to maintain the latter free from projections. With the rivet or post 21 thus assembled relative 45 to the carrier or base plate 11 and the collet or button, the latter is supported in fixed relation to the former, and subject to cooperation with the gripping loop 10 of the garter clasp.

The collet or button is made of molded rubber composition to provide a peculiar novel composite body, comprising a main mass 24, which may consist in a rubber compound tempered or modified by the inclusion of filler material to produce a body of desired shape 55 retaining qualities as well as that degree of surface hardness desired, in combination with which there is provided an interior reenforcing core portion 25, which preferably consists in a tough and highly resilient mass of com- 60 paratively high rubber gum contents. This

core portion 25 extends annularly within the interior of the main mass 24, and may be variously shaped as to its cross-section, although I have formed the S-shape shown in the drawings to be highly satisfactory, since 70 it distributes the extra resilient material thereof to best advantage, both from the standpoint of rendering the collet and button resilient at desired points, as well as from the standpoint of reenforcing the external 75 mass 24 adequately against breaking, splitting, chipping and similar deterioration.

It will be observed that, owing to the novel contour and the internal structure of the collet or button, the same may be made of comparatively large diameter but of little height; and by reason of the large diameter of the shank 16 a better gripping cooperation with the loop 10 is attained since a greater surface contact of material, such as stocking body S, 80 with the collet or button is attained, when such material is engaged over the collet or button and clasped thereto by the embrace of the gripping loop 10. At the same time owing to the hollowed bottom of shank 16, 85 the body or wall of such portion of the collet or button is reduced, so as to increase the resiliency thereof, and consequently such shank portion conforms more readily and snugly to the embrace of the gripping loop 90 10; this latter effect is also increased in effectiveness by the higher resiliency of the shank of the collet or button which is obtained by the resilient core 25, whereby a greater amplitude of deformation under the embrace of the gripping loop may be attained without risk of cracking, splitting or breaking the collet or button. In other words the resiliency of the collet or button is relatively high at the shank, where embrace of the gripping loop occurs, as compared with the resiliency of the head portion. Another advantage of 100 the novel construction of the collet or button, which enhances its efficiency in service, is the tapered contour of the shank and oblique undercut contour of the head thereof, whereby, when the stocking material is engaged over the collet or button, and clasped thereto by the gripping loop 10, not only will said 105 material be smoothly snugged around the head, but the draw or pull on the gripping loop, tending to cause the latter to ride upwardly on the shank, will produce a wedging action tending to more firmly grip the stocking material, and thus prevent relative slipping of the same between the collet or button and gripping loop.

It will be understood that the garter clasp is manipulated, when applying and removing 110 the same from engaged relation to stocking material, in the usual or conventional manner; but with attendant advantages, as above pointed out, which have not heretofore been 115 attained with ordinary collets or buttons as 120 125 130 133

heretofore supplied. With my novel collet or button, I have found that a firm and secure grip on stocking material is obtained, even with the thinnish or most sheer materials, and that, because of the superior resiliency of the collet or button and the comparatively large surface areas provided thereby for engagement with the material, without risk of breaking or injuring the threads 10 of the stocking material, or the starting of "runs" therein from the latter or other causes.

I am aware that many detail changes could be made in the above described construction 15 and many apparently widely different embodiments of this invention could be made without departing from the scope thereof, and consequently it is intended that all matter contained in the above description or shown 20 in the accompanying drawings shall be interpreted as illustrative and not in a limiting sense.

I claim:—

1. In a garter clasp having a button strap 25 and a gripping loop to cooperate therewith, a button on said strap comprising a base-plate mounted on the strap, a post supported by said base-plate, and a resilient collet mounted around said post, said collet having 30 a head portion and a shank footing on said base plate, the bottom of said shank having a hollowed part to provide annular external walls of reduced mass at points which receive the embrace of said gripping loop, whereby 35 the resiliency of the collet at the latter points is increased.

2. In a garter clasp having a button strap, and a gripping loop to cooperate therewith, a button on said strap comprising a base-plate 40 having an upwardly directed perforate hollow conical shoulder portion, a post footed on said shoulder, said post having a riveting lug headed over the under side of said shoulder within the limit of the hollow interior 45 thereof to thus maintain the bottom surface of said base-plate free from external projections, and a resilient collet mounted around said post, said collet having a head portion and a shank footing on said base-plate, the bottom of said shank having a hollowed part 50 to provide external walls of reduced mass at points which receive the embrace of said gripping loop, whereby resiliency of the collet at the latter points is increased.

3. In a garter clasp having a button strap, and a gripping loop to cooperate therewith, a button on said strap comprising a base-plate mounted on the strap, a post supported by said base-plate, and a resilient collet 60 mounted around said post, said collet having a head portion provided with an oblique inwardly undercut periphery and a downwardly tapering shank, the bottom of said shank having a hollowed portion to provide walls in a reduced mass at points which 65

receive the embrace of said gripping loop, whereby the resiliency of the collet at the latter points is increased.

4. In a garter clasp having a button strap and a gripping loop to cooperate therewith, a 70 button on said strap comprising a base-plate having an upwardly directed perforate hollow conical shoulder portion, a post footed on said shoulder, said post having a riveting lug headed over the underside of said shoulder within the limits of the hollow interior thereof to thus maintain the bottom surface of said main base-plate free from external projections, and a resilient collet mounted around said post, said collet having a head 75 portion provided with an oblique inwardly undercut periphery and a downwardly tapering shank, the bottom of said shank having a hollowed portion to provide walls of reduced mass at points which receive the embrace of said gripping loop, whereby the resiliency of the collet at the latter points is increased.

5. In a garter clasp having a button strap and a gripping loop to cooperate therewith, 80 a button on said strap comprising a base-plate having an upwardly directed perforate hollow conical shoulder portion, a post footed on said shoulder, said post having a riveting lug headed over the underside of said shoulder within the limits of the hollow interior thereof to thus maintain the bottom surface of said main body-plate free from external projections, said post having an enlarged head at its upper end, and a resilient collet 85 mounted around said post, said collet having a counter-sunk seat at its upper end for the head of said post, said collet having an annular head portion and a shank depending therefrom, the bottom of said shank having a hollowed part to provide external walls of reduced mass at points which receive the embrace of said gripping loop, whereby resiliency of the collet at the latter points is increased.

6. In a garter clasp having a button strap and a gripping loop to cooperate therewith, a button on said strap comprising a base-plate having an upwardly directed perforate hollow conical shoulder portion, a post foot- 100 ing on said shoulder, said post having a riveting lug headed over the underside of said shoulder within the limits of the hollow interior thereof to thus maintain the bottom surface of said main base-plate free from external projections, said post having an enlarged head at its upper end, and a resilient collet mounted around said post, said collet having a head portion provided with 105 an oblique inwardly undercut periphery and a downwardly tapering shank, the bottom of said shank having a hollowed portion to provide walls of reduced mass at points which receive the embrace of said gripping loop, 110 whereby resiliency of the collet at the latter points is increased.

115

7. In a garter clasp having a button strap and a gripping loop to cooperate therewith, a button on said strap comprising a base-plate having an upwardly directed perforate hollow conical shoulder portion, a post foot- 120 ing on said shoulder, said post having a riveting lug headed over the underside of said shoulder within the limits of the hollow interior thereof to thus maintain the bottom surface of said main base-plate free from external projections, said post having an enlarged head at its upper end, and a resilient collet mounted around said post, said collet having a head portion provided with 125 an oblique inwardly undercut periphery and a downwardly tapering shank, the bottom of said shank having a hollowed portion to provide walls of reduced mass at points which receive the embrace of said gripping loop,

whereby the resiliency of the collet at the latter points is increased.

7. In a garter clasp having a button strap and a gripping loop to cooperate therewith, a button on said strap comprising a base-plate mounted on the strap, a post supported by said base-plate, and a resilient collet mounted around said post, said collet having a head portion and a shank footing on said base-plate, said collet consisting of a body of molded rubber compound having an internal reenforcing core of a different rubber compound which possesses a higher rubber gum content.

15 8. In a garter clasp having a button strap and a gripping loop to cooperate therewith, a button on said strap comprising a base-plate having an upwardly directed perforate hollow shoulder portion, a post footing on said shoulder, said post having a riveting lug headed over the underside of said shoulder within the limits of the hollow interior thereof, and a resilient collet mounted around said post, said collet having a head portion and a shank footing on said base-plate, said collet consisting of a body of molded rubber compound having an internal reenforcing core of a different rubber compound which possesses a higher rubber gum content.

25 9. A collet for garter clasps, comprising a unitary body providing a head portion and a shank depending from said head portion, said body consisting in an external mass of vulcanized compound having an internal core of relatively higher rubber gum content.

30 10. A collet for garter clasps, comprising a unitary body providing a head portion having an obliquely undercut periphery, a tapered shank depending from said head portion, said body consisting in an external mass of vulcanized rubber compound having an internal core of relatively higher rubber gum content.

35 11. A collet for garter clasps, comprising a unitary body providing a head portion having an obliquely undercut periphery, a tapered shank depending from said head portion, said body consisting in an external mass of vulcanized rubber compound having an internal core of relatively higher rubber gum content, said body having an axial bore terminating at its upper end in a countersunk seat of enlarged diameter.

40 12. A collet for garter clasps, comprising a unitary body providing a head portion and a shank depending from said head portion, the bottom of said shank having a hollow portion to reduce the mass of the walls of said shank, said body consisting in an external mass of vulcanized rubber compound having an internal core of relatively higher rubber gum content, and said core extending annularly throughout both the head portion and shank.

45 13. A collet for garter clasps, comprising a

unitary body providing a head portion and a shank depending from said head portion, the bottom of said shank having a hollow portion to reduce the mass of the walls of said shank, said body consisting in an external mass of vulcanized rubber compound having an internal core of relatively higher gum content, said core extending annularly throughout both the head portion and shank, said body having an axial bore terminating at its upper end in a countersunk seat of enlarged diameter. 70

75 14. A collet for garter clasps, comprising a unitary body providing a head portion having an obliquely undercut periphery, a tapered shank depending from said head portion, the bottom of said shank having a hollow portion to reduce the mass of the walls of said shank, said body consisting in an external mass of vulcanized rubber compound having an internal core of relatively higher rubber gum content, and said core extending annularly throughout both the head portion and shank. 80

85 15. A collet for garter clasps, comprising a unitary body providing a head portion having an obliquely undercut periphery, a tapered shank depending from said head portion, the bottom of said shank having a hollow portion to reduce the mass of the walls of said shank, said body consisting in an external mass of vulcanized rubber compound having an internal core of relatively higher rubber gum content, said core extending annularly throughout both the head portion and shank. 90

95 100 In testimony, that I claim the invention set forth above I have hereunto set my hand this 30th day of October, 1929. 105

HENRY J. STUART.
